UNITED STATES PATENT OFFICE.

WALDEMAR W. JACOBS, OF CHICAGO, ILLINOIS.

FRINGE FABRIC.

SPECIFICATION forming part of Letters Patent No. 399,332, dated March 12, 1889.

Application filed August 13, 1888. Serial No. 282,567. (No specimens.)

To all whom it may concern:

Be it known that I, WALDEMAR W. JACOBS, a citizen of the United States of America, residing at Chicago, in the county of Cook and

5 State of Illinois, have invented certain new and useful Improvements in Fringe Fabrics, of which the following is a specification, reference being had therein to the accompanying drawings.

10 Heretofore tassels for fringes had to be wrapped or bound by hand, and had to be connected to the gimp or heading also by hand, all of which was a slow and tedious manipulation, and it is the object of this my invention to produce a fringe fabric made entirely in a loom by the ordinary process of weaving; and with this object in view my invention consists of the article of manufacture hereinafter described and specifically claimed.

15 In the accompanying drawings, Figure 1 represents the manner of weaving the gimp or heading of the fringe and the tassels attached thereto simultaneously during the same operation, and Fig. 2 shows the manner of binding in a double row of tassels independently of the gimp, while Fig. 3 shows a section of a tassel at its wrapping or binding point, showing the warp-threads that form the shed for receiving and binding it.

20 Corresponding letters of reference in the several figures of the drawings designate like parts.

The parts and operation of a hand-loom such as used for this manufacture being well known, and this invention having reference only to the arranging of the warps for accomplishing the desired object, the several figures of the drawings are deemed to be sufficiently explicit without showing the loom itself or

25 any one of its operating elements.

In Fig. 1, A denotes the gimp or heading, which naturally forms a part of fringe of most every description, and a denotes the warp for weaving such gimp, which in the usual manner is passed through the healds of the harness for shedding. Parallel with this warp a for gimp A and the required distance apart therefrom is drawn an additional warp, B, to act as the binder for each individual tassel, 30 which warp B is passed through the healds of a separate harness, each of the two harnesses

to be operated by independent pedals in the usual manner.

C represents the combined strands which form the substance or body of the tassel. 55

The cord that constitutes the hanger or loop d of the tassel is placed with one end in the shed of the warp a, to be caught and held therein, is then passed around the combined strands C, and then its other end is passed upward, and is also inserted into the shed of warp a, so as to form part of the weft in weaving the gimp. The weft b being laid into warp B sufficiently often to form a strong tie for one side of the tassel-neck, the combined 60 strands C, doubled over the hanger-cord d, are passed through the shed of such warp B, which crosses over it, and the weft b' is then laid in on the opposite side of the tassel-neck and is beaten up by the lay or batten of the loom 65 in the usual manner. After a fringe has thus been made in the loom the combined strands C are severed intermediate of the tassel-heads with a pair of scissors, and the warp B is cut away between the weft that forms the binding 70 of each tassel. Thus a perfect tassel, E, is produced, suspended from the upper heading or gimp and bound by weaving in the most substantial manner, abolishing the use of the ordinary now well-known process of wrapping 75 and binding by hand.

For making tassels independently of the gimp or heading, which is to be secured thereto afterward for making the fringe by inserting the ends of their loops or hangers d into the 80 shed of the gimp-warp, I draw through the loom two warps, B' and B², a proper distance apart and parallel with each other, and the combined strands C', I pass zigzag first through the shed of one and then through the shed of 85 the other warp, binding each by the weft in the same manner as described above, and around that portion of the combined strands C' which is doubled up for forming the head of the tassel I pass the loop-cord d', previously to binding the tassel in warp B' or B², 90 all as shown by Fig. 2. After thus completed in the loom the strands C are cut centrally between the warps B' and B², as indicated by dotted lines, and these warps B' B² are also 95 cut away between the binding-wefts of each 100 two tassels.

What I claim is—

The improved fringe fabric which consists, substantially as described, of the heading or gimp A, the hanger-loops secured thereto, and 5 the tassels consisting of the combined yarn-strands passing through and looped around the hanger-loops and bound just below said loops by warp-threads passing around the

tassels and fastened at each side thereof by weft-threads in the ordinary manner.

In testimony whereof I affix my signature in presence of two witnesses.

WALDEMAR W. JACOBS.
